UNITED STATES PATENT OFFICE.

ANDREW LITTLE, OF NEW YORK, N. Y.

DESIGN FOR PRINTING-TYPE.

Specification forming part of Design No. **6,761**, dated July 8, 1873; application filed June 20, 1873.

To all whom it may concern:

Be it known that I, ANDREW LITTLE, of the city, county, and State of New York, have originated and produced a new and original Design for Printing-Type, of which the following is a specification:

The nature of my design is fully shown in

the accompanying typographic impression, to which reference is had.

What I claim as new is—

The design for printing-type, as shown.

Witnesses: ANDREW LITTLE.

A. SIDNEY DOANE,
WM. HASTINGS.
